UNITED STATES PATENT OFFICE.

GUSTAVE MELING, OF FLUSHING, NEW YORK.

AMUSEMENT APPARATUS.

Application filed October 3, 1927. Serial No. 223,719.

This invention relates to improvements in amusement apparatus and has particular reference to a ride for amusement parks and like places.

5 The primary object of the invention resides in an amusement ride which includes a course for the travel of passenger cars thereover and to which the passengers riding in the cars are given an unusual and exciting experience 10 as the cars are subjected to lateral and vertical movements during their travel over the course which imparts to the passengers the sensation of an automobile travelling over an uneven roadway.

15 Another object of the invention is to provide an amusement apparatus in which passenger cars simulating automobiles are used, the chassis of the cars being movable over an even surface while the body is swivelly 20 supported thereon for vertical and lateral movements with respect thereto.

Another object is the provision of an amusement apparatus including a continuous course for the travel of passenger cars there- 25 over, and which cars are propelled by a continuous cable to which the cars may be removably connected, there being a suitable means for automatically bringing the cars to a stop when reaching the starting point by 30 releasing their connection with the cable, and an automatic means for engaging the cars with the cables when starting the same.

With these and other objects in view, the invention resides in certain novel construction and combination and arrangement of parts, the essential features of which are hereinafter fully described, are particularly pointed out in the appended claims, and are illustrated in the accompanying drawing, in 40 which:—

Figure 1 is a side elevation of a portion of the course of my improved amusement apparatus showing passenger cars thereon.

Figure 2 is a top plan view.

45 Figure 3 is a vertical sectional view through one of the passenger cars.

Figure 4 is a vertical transverse sectional view on the line 4—4 of Figure 3.

Figure 5 is a horizontal sectional view on the line 5—5 of Figure 3.

Figure 6 is a side elevation of one of the passenger cars.

Figure 7 is a vertical transverse sectional view on the line 7—7 of Figure 6.

55 Figure 8 is a plan view of the course with the cars removed therefrom.

Referring more particularly to the drawings, the numeral 10 designates a continuous course which may be of any configuration, but in Figure 8 of the drawings, I have shown 60 the same as elliptical. The course 10 comprises a track 11 which is U-shape in cross section and which includes a horizontal base 12 and vertical sides 13 rising therefrom in even spaced relation throughout. The tops 65 of the vertical walls are provided with outer rails 14 and inner rails 15 at certain spaced intervals about the course and which outer and inner tracks are undulated as at 16 and 17 respectively, for a purpose to be herein- 70 after described. The undulations on one side wall 13 may be staggered with respect to the undulations of the tracks on the opposite side wall. The side walls 13 are cut-away at certain points along the course as at 18 for a 75 distance below the valleys of the undulations and arranged within the course between the side walls 13 is a cam slot 19 which extends the length of the cut-away portions 18.

Movable over the course 10 are passenger 80 carrying cars 20 simulating automobiles, each of which includes a chassis frame 21, front wheels 22 and rear wheels 23 which ride over the base 12 and which are held in spaced relation to the side walls 13 by rollers 24 85 which engage said side walls, and which rollers are journaled in brackets 25 fixed and extending from the chassis frame 21. A hood 26 is mounted forward on the chassis frame while a body 27 is movably supported 90 upon the chassis frame rearward of the hood.

The body 27 comprises any number of passenger compartments or seats 28. Journaled on opposite sides of the body are front flanged wheels 29 and rear flanged wheels 30 for travel 95 over the inner and outer rails 15 and 14 respectively. The body is supported in spaced relation to the chassis frame by an arcuate series of rollers 31 journaled in and extending above the plate 32 forming part of the chassis frame 21. The bottom of the body rests upon the rollers for lateral swinging movement with respect to the chassis. Extending downward from the bottom of the body through an arcuate slot 33 in the plate 100 32 is an arm 34 which carries a roller 35 adapted to enter the cam slots 19 arranged about the course and by which a lateral movement is imparted to the body. A bracket 36 is fixed to the front of the body and extends forward 105 from the bottom thereof and has a socket 37 at the free end thereof for the reception of a ball 110.

38 provided on one end of a link 39 pivoted to a king pin 40 fixed to the chassis frame. Equalizing springs 41 encircle the king pin on opposite sides of the link and which permit of the forward and backward rocking of the body during the travel of the wheels 29 and 30 over their respective undulated rails.

From the description thus far, it will be seen that as the passenger cars travel over the course, a bumping action is imparted thereto as the wheels 29 and 30 ride over the undulated rails, thus imparting the sensation of an automobile travelling over an uneven road. As the cars reach the cam slots 19, the roller 35 enters the slots and by reason of their serpentine shape, causes the cars to swing from one side to the other. The distance of swinging movement of the body is determined by the walls of the slots 19.

For the purpose of propelling the cars over the course, I provide an endless cable 42 having knots 43 provided thereon at suitable spaced intervals. The cable moves within a recess 44 provided in the inner face of the inner wall 13. The cable 42 passes over a driving pulley wheel 45, driven by a pulley 46 mounted on the same shaft therewith over which a belt or cable 47 passes. The cable 47 is also looped about a pulley 48 fixed to the shaft of a motor 49. Movable into engagement with the knots 43 on the cable 42 is the forked end 50 of a sliding rod 51 mounted beneath the chassis frame. An actuating lever 52 is pivoted to the plate 32 beneath the hood 26, and has its lower end offset as at 53 for normal disposition in the path of a cam block 54 mounted on the base 12 adjacent the starting and stopping point marked A. A spring 55 has one of its ends fixed to the top end of the lever 52 while its other end is attached to a stationary part such as the hood 26. A link 56 has its ends pivotally connecting the inner end of the rod 51 and the lever 52 whereby the spring tends to normally force the lever to a position to extend the fork 50 into the path of the knots on the cable. As one of the knots engages behind the fork, the car will be propelled forward over the course. However, when the cars have circled the course, the offset end 53 of the lever will come in contact with the cam face on the cam block 54 which forces the lever to the dotted line position shown in Figure 7 of the drawings whereupon the rod 51 is retracted against the action of the spring 55, thus causing the forked end 50 to move out of the path of the knots. The cars are now disconnected from the cable and remain stationary until the passengers have been discharged and other passengers permitted to enter. When starting the ride, the cars are manually pushed for a distance to cause the offset 53 to clear the end of the cam block 54, at which time the spring 55 actuates the lever 52 to extend the fork rod 51 into the path of the knots on the cable

whereupon the car is propelled forward. The control means being in the hood is concealed from view and cannot be tampered with during the ride by passengers. The liabilities of collision between the cars is practically impossible as the cars are always kept at the same distance apart during the entire ride, thus assuring absolute safety to passengers.

From the foregoing description, it will be seen that I have provided an amusement ride for installation in amusement parks and like places, which provide an unusual sensation to the passengers as the body of the cars are movable vertically and horizontally with respect to the path of travel.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

1. An amusement apparatus including a courseway, passenger cars each embodying a chassis having wheels movable over said courseway and a body yieldingly mounted on said chassis, inner and outer undulated rails arranged along said courseway on opposite sides thereof, the undulations of the inner and outer rails being staggered with respect to each other, and sets of wheels journaled on said body and respectively movable over said inner and outer rails.

2. An amusement apparatus including a courseway, passenger cars each embodying a chassis having wheels movable over said courseway and a body connected thereto by a universal joint, undulated inner and outer rails arranged along said courseway at suitable spaced intervals and disposed on opposite sides thereof, the undulations of the respective inner and outer rails being staggered with respect to each other, sets of wheels journaled on said body and respectively movable over said inner and outer rails, a cam element provided in said courseway intermediate the lengths of rails, and an arm extending from said body in the path of said cam element for co-acting engagement therewith.

3. An amusement apparatus including a courseway of substantially U-shape in cross section, cars movable over said courseway, each car embodying a chassis having wheels and a body flexibly connected to said chassis, guide rollers provided on said chassis engaging the side walls of said courseway to hold said wheels in spaced relation therefrom, inner and outer undulated rails provided on the top of the side walls of said courseway, the undulations of the inner and outer rails being staggered with respect to each other and sets

of wheels journalled on said body for respective engagement with said inner and outer uneven rails.

4. An amusement apparatus including a courseway of substantially U-shape in cross section, cars movable over said courseway, each car embodying a chassis having wheels and a body flexibly connected to said chassis, guide rollers provided on said chassis engaging the side walls of said courseway to hold said wheels in spaced relation therefrom, spaced lengths of inner and outer uneven rails provided on the top of the side walls of said courseway, sets of wheels journalled on said body for respective engagement with said inner and outer uneven rails, a cam element within said courseway intermediate the lengths of rails, and a member extending from said body in the path of said cam ele-
20 ment.

5. An amusement apparatus including a courseway having a cam slot arranged therealong, a passenger car movable over said courseway, said passenger car embodying a wheeled chassis and a body pivoted thereto for lateral horizontal swinging movement with respect to said chassis, and a member extending from said body and movable within said cam slot for imparting lateral swinging movements to said body during the travel of 25 30 said car over said courseway.

6. In an apparatus of the class described, a passenger car comprising a wheeled chassis, a series of arcuately arranged rollers journalled in said chassis, and a body pivoted to 35 said chassis and supported upon said series of rollers for lateral movement thereover.

In testimony whereof I have affixed my signature.

GUSTAVE MELING.
